UNITED STATES PATENT OFFICE.

PHILIP S. McCROSKEY, OF NETAWAKA, KANSAS.

TRAIN-ORDER CABINET.

1,291,046.

Specification of Letters Patent.

Patented Jan. 14, 1919.

Application filed September 14, 1916. Serial No. 120,130.

To all whom it may concern:

Be it known that I, PHILIP S. McCROSKEY, a citizen of the United States, residing at Netawaka, in the county of Jackson, State 5 of Kansas, have invented certain new and useful Improvements in Train-Order Cabinets; and I do hereby declare the following to be a full, clear, and exact description of the invention, such as will enable others skilled in the art to which it appertains to 10 make and use the same.

This invention relates to a train order cabinet.

In order that this invention may be more 15 readily understood it is here stated that when a railway telegraph operator at a signal tower takes an order for the control of trains he must at the same time release the train order board by hand so that the train 20 will be stopped. There are several different forms of orders of some of which there must be but one carbon and of others of which various numbers of carbons must be made. In order that the work of taking 25 the orders may be facilitated the carbon sheets are put in place beforehand so that when an order is received the proper blanks are selected and the order written thereon. Of course, should the operator fail to 30 release the train order board when taking the order the train will be allowed to proceed beyond the tower and consequently the possibility of a collision will arise.

It is therefore an object of my invention 35 to provide a cabinet for the order blanks which is so constructed that upon the withdrawal of one of the blanks therefrom the train order board will automatically be released.

It is still further an object of my invention 40 to so construct the device that the release will be accomplished irrespective of the blank which is withdrawn.

With these and other objects in view such 45 as will appear as my description progresses, my invention comprises the combination and arrangement of parts as set forth in and falling within the scope of the appended claims.

0 In the drawings:—

Figure 1 is an elevation of a train order cabinet constructed in accordance with the invention, showing several train order holders therein, and the lever for controlling the 5 train order board being partly broken away;

Fig. 2 is a vertical longitudinal sectional view through the cabinet;

Fig. 3 is a fragmentary side elevation showing in detail the position of the detents when the train order holders are within the 60 cabinet;

Fig. 4 is a fragmentary vertical transverse sectional view showing the locking bar or rod in position for locking the train order board in raised or signaling position; 65

Fig. 5 is an enlarged fragmentary horizontal sectional view showing one of the detents in locked position with the locking rod;

Fig. 6 is a fragmentary perspective view 70 of one of the train order holders showing in detail the trip cam;

Fig. 7 is an enlarged fragmentary vertical longitudinal sectional view showing one 75 of the train order holders within the cabinet and the normal position of the locking rod or bar;

Fig. 8 is a fragmentary vertical sectional view showing by full lines the released position of the train order controlling lever 80 and by dotted lines the locked position thereof.

Similar reference characters indicate corresponding parts throughout the several views in the drawings. 85

Referring to the drawings in detail, A designates generally a train order cabinet which is in the form of a box-like body 1 open at its front and closed at its bottom, top, sides and back. The inner faces of the 90 sides of the body 1 are formed with spaced horizontally disposed guide grooves 2 which extend from the open front to the closed back of the body and constitute runways for the removable train order holders 3 each including a base 3^a and a spring clip 3^b, the latter being fastened upon the base 3^a and is adapted to detachably hold a plurality of train order blanks and carbons upon the base 3^a of the order blank holder. 95

The cabinet A is adapted to be located at a station or other predetermined point at a railway track and upon the top of the body 1 near the rear thereof is a housing 4 in which is swingingly supported a vertically movable controlling lever 5, which is mounted upon a horizontal pivot 5^a journaled in said housing, and this lever 5 is adapted to be connected in any suitable manner with a train order board capable of 105 110

movement to a signaling or non-signaling position, the train order board being not shown, and is of any conventional form.

The controlling lever 5 has connected thereto a coiled spring 6 which is trained about the pivot 5^a and fixed in any suitable manner to the housing, the spring being designed to throw the lever 5 when released to an upright position for the lowering of the train order board to non-signaling position.

The pivoted end of the lever 5 is formed with a rounded edge 7 serving as a cam and also provided with a shoulder 8 for permitting the locking of the lever 5 in lowered position in a manner presently described.

Supported for vertical sliding movement in a suitable guideway intersecting the grooves 2 in one side of the body 1 and disposed vertically is a locking bar or rod 9 which at the innermost longer edge is formed with spaced notches 10 through which are adapted to slide the holders 3 when the bar or rod 9 is in lowered position, the said rod or bar being automatically raised under the action of a coiled expansion spring 11 mounted in the bottom of the body 1 and acting upon the lower end of said bar or rod. The bar or rod 9 when in raised position engages with the shoulder 8 on the lever 5 when lowered to lock the same against vertical swinging movement and thereby holding the train order board in signaling position. The spring 11 is supported by a base plate 12 secured to the bottom of the body 1 of the cabinet as is clearly shown in Fig. 4 of the drawings.

The train order holders each in the base 3^a thereof at the rear corner of one side is formed with a recess 13 in which is fixed a tripping runner 14 formed with the rearwardly beveled edge 14^a to engage the lower end edge of the notch 10 in the bar or rod 9 when in raised position to cause the lowering of said bar or rod on the pulling of the holder 3 from the cabinet, the bar or rod 9 when raised being extended into the recess 13 for the automatic tripping thereof by the runner 14 when removing the holder 3 from the cabinet. The position of the bar or rod 9 when raised and within the recess 13 in the base 3^a of the holder 3 is clearly shown in Fig. 7 of the drawings.

Mounted on the outer face of the side adjacent to the bar or rod 9 of the body 1 is a plurality of latch detents 15 each of which is swingingly supported upon a vertical pivot 16 (see Fig. 3 of the drawings) and these detents 15 are confined within a chamber 17 formed in the side of the body and swinging horizontally therein. Each detent is formed with a right angular wing 18 adapted to work through a suitable slot 19 to project into the groove 2 adjacent thereto,

the wing being formed with a beveled edge 18^a against which acts the inner end of the base 3^a of the holder 3 when moved inwardly in the groove 2 in the cabinet to automatically swing the detent 15 outwardly of the groove. The contracted portion 18^b formed by the beveled edge 18^a of the wing 18 serves as a latch to engage in a slot 19 formed in the outer longer side edge of the bar or rod 9, it being understood of course that a plurality of slots 19 are provided in the bar or rod 9, and the same are located opposite the notches 10 so that any one of the detents 15 will lock the bar or rod 9 in lowered position against the resistance of the spring 11 when any one of the holders 3 have been extracted from the cabinet.

The chamber 17 is closed by a cover plate 20 and suitably fastened within said chamber to act against the detent 15 are leaf springs 21 which urge the detents inwardly for locking engagement with the bar or rod 9 when lowered.

When the holders 3 are within the cabinet A the bar or rod 9 is in raised position and engaged with the lever 5, holding it against swinging movement and this lever controls the train order board thus sustaining the same in signaling position, the bar or rod 9 being engaged with the shoulder 8 on said lever 5.

On withdrawing any one of the holders 3 from the cabinet the runner 14 acts upon the lower end edge of the companion notch 10 in the bar or rod 9 causing the latter to be lowered thereby releasing said bar or rod from its engagement with the lever 5 and the spring 6 becomes active upon the lever to raise the same, thereby lowering the train order board from signaling position thus indicating to an approaching train that the train order holder has been removed from the cabinet. The removal of the train order holder is for the purpose of taking an order therefrom by a trainman of a preceding train. On the withdrawal of the holder the detent 18 next thereto, the series of which when the bar or rod 9 is raised are unlocked therefrom, will engage in the slot 19 in said bar or rod 9 and thus lock the same in lowered position to prevent the raising thereof. When all of the holders have been placed within the cabinet the detents 15 will be automatically disengaged from the bar or rod 9 by the action of the holders 3 upon the beveled edges 18^a of the wings 18 so that the spring 11 will move the bar or rod 9 to raised position for the engagement thereof in the recesses 13 in the bases 3^a of the holders 3 and upon depressing the lever 5 the cam edge 7 will act upon the bar or rod 9 to cause the same to lock with the shoulder 8 of said lever and thus sustain it in lowered position.

It will thus be seen that the device will

automatically release the train order board upon the withdrawal of any one of the train order holders from the cabinet A as will be clearly apparent.

5 What is claimed is:—

1. The combination with a cabinet, of a locking lever mounted thereon and having a shoulder, a vertically slideable rod mounted in said cabinet and engageable with the shoulder on said lever to lock the same in one position, means for urging the rod into locking engagement with the lever, a plurality of train order holders removably mounted in the cabinet, runners on said holders for depressing the rod on the removal of any one of the holders from the cabinet to automatically release the locking lever, and means for locking the rod in lowered position when the holder has been removed and automatically releasing said rod when replacing the holder in the cabinet.

2. The combination with a cabinet having a plurality of slidably removable blank holders therein, a locking lever on said cabinet, a rod for engaging the lever to lock the same in a predetermined position, means on the holders to act upon the rod for releasing the same on removal of any one of the holders from the cabinet, and spring held detents for locking engagement with the rod when lowered and automatically controlled by the holders on the removal of any one of the same from the cabinet and adapted to be released from the rod on replacing the holders in the cabinet.

10 15 20 25 30 35 In testimony whereof, I affix my signature, in the presence of two witnesses.

PHILIP S. McCROSKEY.
